UNITED STATES PATENT OFFICE.

JAMES E. PEIRCE, OF WEST BOYLSTON, MASSACHUSETTS.

IMPROVEMENT IN TRACE-CONNECTIONS.

Specification forming part of Letters Patent No. **59,258**, dated October 30, 1866.

To all whom it may concern:

Be it known that I, JAMES E. PEIRCE, of West Boylston, in the county of Worcester and State of Massachusetts, have invented an Improved Whiffletree and Trace Connection; and do hereby declare the same to be fully described in the following specification and represented in the accompanying drawings, of which—

Figure 1 is a top view, and Fig. 2 an end elevation, of it as applied to a whiffletree, it being shown in a closed state. Fig. 3 is a top view, and Fig. 4 is an end elevation, of it as open and ready for the reception of a trace.

A bent arm, A, extends from one end of a trace-receiving pin, B, fixed in one end of a whiffletree, C, and so as to project therefrom in manner as represented.

A guard, D, formed as shown in the drawings, turns on the bent arm and carries a spring-latch, E, to catch upon an angular projection, F, or part of the trace-pin B. The said pin is recessed or notched, as shown at *a*, close to the angular projection, and for the purpose of receiving the guard a shield, b, which projects from the guard, enters the notch while the latch is in the act of being caught by the projection F. The said shield b extends between the latch and the end of the whiffletree, and serves to prevent the trace while on the pin from contact with the latch. The shield thus completely isolates the trace from the latch. Were it not for such shield so arranged with respect to the latch, and operating with the guard to keep the trace on the pin, such trace while in use would be likely to disconnect the latch from the pin, in which case, were the guard to be thrown up by any cause, the trace might slip off the pin.

A portion, *c*, of the guard is projected in front of the latch, and serves as a rest for one finger of a person's hand while in the act of unlatching the latch from the projection F.

To accomplish the separation of the two, he has only to pinch the portion *c* and the lower part of the latch between his thumb and forefinger until he may have moved the latch sufficiently to enable him to lift the guard.

From the above it will be seen that the said guard, as constructed, performs several functions—that is, it serves with the latch to hold the trace on the pin. The part or shield *b* answers to keep the trace from disconnecting the latch from the pin. The part *c* serves as a rest for one finger while another or the thumb of the same hand may be in the act of moving the latch.

Having thus described my invention, what I claim, and desire to secure by Letters Patent, is as follows:

1. The combination as well as the arrangement of the shield *b* with the guard D and its latch applied to the trace-pin, as set forth.
2. The combination of the finger-rest *c* with the guard D and its latch, applied and arranged in manner, and so as to operate with the trace-pin, substantially as specified.
3. The combination of the notch *a* in the trace-pin with the shield, the guard, and the spring-latch, arranged together, and so as to operate with the said trace-pin, substantially as hereinbefore set forth.

JAMES E. PEIRCE.
